(57) **CLAIM**

The ornamental design for a GPS module housing, as shown and described.

DESCRIPTION

FIG. 1 is a front perspective view of the GPS module housing according to an aspect of the present invention.

FIG. 2 is a rear perspective view of the GPS module housing illustrated in FIG. 1.

FIG. 3 is a front view of the GPS module housing illustrated in FIG. 1.

FIG. 4 is a rear view of the GPS module housing illustrated in FIG. 1.

FIG. 5 is a first side view of the GPS module housing illustrated in FIG. 1.

FIG. 6 is a second side view of the GPS module housing illustrated in FIG. 1.

FIG. 7 is a top view of the GPS module housing illustrated in FIG. 1; and,

FIG. 8 is a bottom view of the GPS module housing illustrated in FIG. 1.

The surface shading and broken lines shown in FIGS. 1-8 represent portions of the GPS module housing that form no part of the claimed design.
